UNITED STATES PATENT OFFICE.

DAVID W. TAYLOR, OF WASHINGTON, DISTRICT OF COLUMBIA, ASSIGNOR TO GENERAL ELECTRIC COMPANY, A CORPORATION OF NEW YORK.

CONTROL OF MOTOR-OPERATED DOORS.

No. 868,793.

Specification of Letters Patent.

Patented Oct. 22, 1907.

Application filed May 14, 1906. Serial No. 316,806.

To all whom it may concern:

Be it known that I, DAVID W. TAYLOR, a citizen of the United States, residing at Washington, District of Columbia, have invented certain new and useful Improvements in Control of Motor-Operated Doors, of which the following is a specification.

My invention relates to the control of motor-operated devices, such as bulk-head doors on shipboard, although it is not limited to this particular application, but is applicable to the control of any motor-operated device which must be controlled both locally and from a distance.

In a control system for bulk-head doors, it is essential that all doors should be simultaneously controllable from a distant point, and also that each individual door should be controllable locally independently of the distant control. The man at the door should be able to take the control away from the distant station, as long as he keeps his hand on the controller, but as soon as he releases it, it should be under control of the distant station.

The object of my invention is to provide simple and efficient means for such control, and consists in providing a motor controller with means tending to turn it to the position for connecting the motor for lowering the door, and with other means tending to hold the controller at off position and normally balancing the first means, and means controllable from a distance for rendering the second means inoperative so as to allow the controller to be moved to lowering position.

More specifically considered, my invention consists in providing a motor controller with a spring tending to move it to lowering position, a second spring tending to hold it in off position and normally over-powering the first spring, and a tripping magnet adapted to disengage the controller from the second spring so as to allow the first spring to move the controller to lowering position. With this arrangement the controller is normally held at off position, but a man at the door may move it to either raising or lowering position against the tension of one spring or the other, while at the same time by energizing the tripping magnet from the distant station, the second spring is disengaged from the controller allowing the first spring to move the controller to connect the motor for lowering the door. Thus, all the doors are controllable from a distance so that they may be simultaneously closed, while at the same time a man at the door can control its movement independently of the distant station, and prevent the door from closing as long as he keeps his hand on the controller.

My invention will best be understood by reference to the accompanying drawings, in which

Figure 1 shows a bulk-head door provided with a controller and controlling switch; Fig. 2 shows diagram-

matically the circuits of the motor and controlling switch; Fig. 3 shows an end view of the controller with the casing removed, taken in cross-section in the plane indicated by the dotted line 3-3 in Fig. 4; Fig. 4 shows a cross-sectional side view of the controller; and Fig. 5 shows a detail of the connection between the controller and the tripping magnet.

Referring first to Fig. 1, M represents an electric motor carrying on its shaft the worm w engaging the worm-wheel W. On the shaft of the worm-wheel is mounted the pinion P, which engages a rack R carried by the door D vertically movable in the guide G. With this arrangement the door is raised or lowered, according to the direction of rotation of the motor.

C represents the motor controller which is provided with an operating shaft h carrying at each end a hand-wheel H.

The circuit connections are shown diagrammatically in Fig. 2. The contacts of the controller C are shown developed on a plane surface and comprise seven stationary fingers c¹ to c⁷, and movable contacts, as shown.

a a' represent line-wires carrying the current for the motor derived from the generator or other suitable source A.

B represents the tripping magnet, the circuit of which is controllable from the distant station S.

The motor circuits are as follows: If the movable contacts of controller C are moved downward into engagement with the stationary contact fingers the following circuit may be traced. From line-wire a, contact c⁷, contact c⁶, through the motor field, contact c⁴, contact c³, resistance r', motor armature, contact c¹, contact c², line-wire a'. The motor circuit is thus closed and the motor is connected for raising the door. The resistance r' is included in circuit with the motor so as to limit the motor current and prevent an excess of current-flow if the door reaches the end of its travel before the current is cut off.

If the movable contacts are moved upwards into the other operative position of the controller, a circuit may be traced as follows: from line-wire a, contact c⁷, contact c⁴, through the motor field in the opposite direction, contact c³, contact c⁶, resistance r¹, through the motor armature and resistance r² in parallel to contacts c¹ and c⁵, respectively, to contact c², to line-wire a'. The motor is thus connected for lowering the door.

The purpose of the resistance r² in shunt to the motor armature is to increase the field strength of the motor, so as to prevent the motor from racing when lowering the door, and to give it a strong torque for forcing the door into closed position.

The circuit of the tripping magnet B is controllable from the distant station S, as is apparent from an inspection of the diagram, and by this means the con-

troller may be released from the second operating spring so as to move it to the proper position for closing the motor circuit for lowering the door.

The construction of the controlling switch and tripping magnet is shown in Figs. 3, 4 and 5. In these figures, C represents the movable contact member which is mounted fast on the operating shaft *h*, which is provided at both ends with hand-wheels *H*. A spiral spring *D*, surrounding the shaft and abutting at one end on one of the bearings of shaft *h*, tends to turn the controller C in a clockwise direction as viewed in Fig. 3, so as to bring the stop *e* carried by the controller into engagement with the stationary stop *E*; this being the lowering position of the controller. The controller is, however, normally held in off position, as shown, by means of the lug *F* carried by the controller which is engaged by a similar lug *I* carried by the member *J*. This member *J*, which is loosely mounted on the shaft *h*, is provided with a spiral spring *D'* which tends to rotate it in the opposite direction to that in which the spring *D* tends to rotate the controller, and which also acts to hold the lug *I* normally in engagement with the lug *F* on the controller. The spring *D'* is stronger than the spring *D*, and consequently over-balances it and holds the lug *k*, carried by the member *J*, in engagement with the stop *K*. This is clearly shown in Fig. 4. The controller is thus prevented from moving to lowering position under the tension of spring *D*, and is held in off position, as shown. The connection between the controller C and the member *J* is clearly shown in Fig. 5. Although the controller is thus held in off position it is evident that it may be moved by hand to raising position, compressing the spring *D*, or to lowering position, compressing the spring *D'*.

The member *J*, which is movable axially, as well as circumferentially on the shaft, forms the armature or core of the tripping magnet *B*; the circuit of which, as has been heretofore explained, is controllable from the distant station. When the magnet *B* is energized, the member *J* is moved to the right as viewed in Fig. 4, compressing spring *D'* and releasing lug *F* from its engagement with lug *I*. The controller C is then free to turn to lowering position under the influence of spring *D*. After the magnet *B* is deenergized, the controller C may be returned into engagement with the member *J* by moving it manually to off position.

I do not desire to limit myself to the particular construction and arrangement of parts here shown, but aim in the appended claims to cover all modifications which are within the scope of my invention.

What I claim as new and desire to secure by Letters Patent of the United States, is,—

1. In combination with a motor, a manually-operated controlling switch therefor having a plurality of operative positions, means tending to move said switch to an operative position, means normally holding said switch in off position, and means controllable from a distance for disengaging said switch from said holding means.
2. In combination with a motor, a manually-operated controlling switch therefor having a plurality of operative positions, means tending to move said switch to an operative position, a second spring normally balancing the first and holding said switch in off position, and a magnet adapted when energized to disengage said switch from said second spring.

3. In combination with a motor, a manually-operated controlling switch therefor having a plurality of operative positions, a spring tending to move said switch to an operative position, a second spring normally balancing the first and holding said switch in off position, and means controllable from a distance for disengaging said switch from said second spring.

4. In combination with a motor, a manually-operated controlling switch therefor, opposing springs arranged to hold said switch yieldingly in off position, and means controllable from a distance for disengaging said switch from one of said springs.
5. In combination with a motor, a manually-operated controlling switch therefor, opposing springs arranged to hold said switch yieldingly in off position, a tripping magnet adapted to disengage said switch from one of said springs, and means at a distance for controlling the circuit of said magnet.
6. In combination, a system of doors, a motor for operating each door, a manually-operated controlling switch for each motor, opposing springs arranged to hold each switch yieldingly in off position, a tripping magnet for each switch adapted to disengage it from one of said springs, and means at a distant point for simultaneously energizing the tripping magnets of all the switches.

7. In combination, a system of doors, a motor for operating each door, a manually-operated controlling switch for each motor, a spring tending to move each switch to an operative position, a second spring normally balancing the first and holding the switch normally at off position, an electro-magnet for each switch adapted when energized to disengage it from its second spring, and means at a distant point for simultaneously energizing the several magnets.
8. In a controlling switch for electric motors, an operating shaft, a contact member mounted thereon, a spring tending to move said contact member to an operative position, a member loosely journaled on said shaft and adapted to engage said contact member, a spring acting upon said second member and balancing the first spring, and a tripping magnet adapted to disengage said contact member from said second member.

9. In a controlling switch for electric motors, an operating shaft, a contact member mounted thereon, a spiral spring surrounding the shaft and tending to move said contact member to an operative position, a second member loosely journaled on the shaft, a second spiral spring acting on said second member to hold it normally in engagement with said contact member and balancing the first spring, and a tripping magnet adapted to disengage said contact member from said second member.
10. In a controlling switch for electric motors, an operating shaft, a contact member mounted thereon, a spring tending to move said member to an operative position, a magnet winding concentric with said shaft, a core therefor journaled on said shaft and axially movable thereon, and a spring arranged to hold said core normally in engagement with said contact member and to balance the first spring.

11. In combination with a motor, a manually-operated controlling switch therefor having a plurality of operative positions, means tending to move said switch to an operative position, means normally holding said switch in off position, and means controllable from a distance for rendering said holding means inoperative.

In witness whereof, I have hereunto set my hand this tenth day of May, 1906.

DAVID W. TAYLOR.
